UNITED STATES PATENT OFFICE.

PHILIP DUPHINEY, OF WATERBURY, CONNECTICUT.

CEILING HANGER.

Application filed July 29, 1925. Serial No. 46,789.

To all whom it may concern:

Be it known that I, PHILIP DUPHINEY, a citizen of the United States, and a resident of Waterbury, county of New Haven, and State of Connecticut, have invented certain new and useful Improvements in Ceiling Hangers, of which the following is a specification.

This invention relates to ceiling hangers, and more particularly to hangers adapted to be suspended from the joists under a floor for holding an expanded metal lath which forms the support for the plaster ceiling of the room beneath.

One object of this invention is to provide a hanger of the above nature in which the so-called "cross-furring" strips, formerly used to support the metal lath, will be eliminated.

A further object is to provide a hanger of the above nature so constructed as to absorb shocks from the floor above, and to thereby prevent the plaster of the ceiling from cracking, swelling or splitting off from the metal lath.

A further object is to provide a ceiling construction which will be unaffected by shrinkage of the joists or other wooden parts of the building.

A further object is to provide a ceiling construction in which the metal lath is connected by wires to a plurality of channel irons which are suspended from the floor joists by a plurality of resilient metal hangers.

A further object is to provide a device of the above nature which will be simple in construction, inexpensive to manufacture, easy to install, and very efficient and durable in use.

With these and other objects in view, there have been illustrated on the accompanying drawings, two forms in which the invention may be conveniently embodied in practice.

Fig. 1 represents a side view of the first form of ceiling hanger, which is made from bent metal wire.

Fig. 2 is an end view of the same.

Fig. 3 is a perspective view of a modified form of ceiling hanger, said hanger being made of bent strip metal and being adjustable.

Fig. 4 is a transverse sectional view showing part of a floor and ceiling construction in which hangers embodying both forms of the invention have been installed.

Fig. 5 is a longitudinal sectional view of the floor and ceiling construction showing a side view of two of the strip metal hangers.

Fig. 6 is a plan view of a portion of the expanded metal lath for supporting the plaster of the ceiling.

In the construction of plaster ceilings in wooden frame buildings, it has been customary for some time to support the plaster upon a sheet of open expanded metal lath, said sheet having been previously stapled to a series of "cross-furring" strips which in turn were nailed to the joists of the floor above. This type of construction has been found somewhat unsatisfactory in use because of the fact that shocks and vibrations on the floor above were directly transmitted through the joists and "cross-furring" strips to the plaster of the ceiling beneath. Strains were thus set up in the plaster often causing it to crack, swell, become grooved, or even to split off from the metal lath.

By means of the present invention, the above and other disadvantages have been avoided. This has been accomplished by wiring the metal lath to a series of channel irons which are themselves suspended in a plurality of shock-absorbing resilient hangers, rigidly connected at their top portions to the joists of the floor above.

Referring now to the drawings in which like reference numerals denote corresponding parts throughout the several views, the first form of hanger is disclosed in Figs. 1 and 2, and comprises a piece of stiff metal wire bent to form an upper loop 10, which is adapted to be hung upon a nail or screw driven into the floor joist 11. Below the loop 10, the hanger consists of a straight portion 12 which is connected to an intermediate U-shaped portion 13 having a curved end 14. The lower leg 15 of the U-shaped portion 13 is shorter than the upper leg 16, whereby the bottom part 17 of the hanger will be offset from the upper portion 12. By means of this construction, it will be seen that there will be no danger of the lower part 17 of the hanger coming into contact with the floor joist 11 from which the hanger is suspended.

The base 18 of the hanger is bent at right angles to the lower part 17 thereof, and is adapted to form a seat for a channel iron 19 adapted to be connected, as by suitable wires 21, to a sheet of metal ceiling lath 20. A wire ring 22 is adapted to surround the

legs 15 and 16 of the loop 13, whereby the weight of the ceiling beneath will be supported.

- In order to prevent sudden shocks and vibrations on the floor above from being transmitted to the ceiling beneath, the upper leg 16 of the U-shaped loop 13 of the hanger is reduced in thickness at 22 for a portion of its length, whereby said upper leg 16 will have a greater resiliency than the lower leg 14 thereof. It has been found in practice that when the present improved form of ceiling construction is installed, heavy weights may be moved freely about on the floor above without injury to the ceiling beneath. This result is due to the shock-absorbing action of the reduced portion 22 of the upper leg 16 of the U-shaped loop.

In use, the hangers will preferably be spaced apart in alinement along the joists 11 at any desired intervals, according to the weight of the ceiling to be supported.

It will be understood that the hangers may be attached to all of the flooring joists or only on alternate joists, as conditions may require.

The adjustable second form of ceiling hanger is shown in Figs. 3 and 5, and at the right of Fig. 4. This form of hanger is constructed from a strip of sheet metal and comprises a flat upper section 23 having apertures 24 and 25, by means of which the hanger may be suspended from a floor joist 26, as by screws 24^a and 25^a. The lower portion 27 of this form of hanger is parallel to and offset from the upper portion 23 so that said lower portion will hang entirely free and spaced from the joist 26. The base 28 of the adjustable hanger is bent in a horizontal plane at right angles to the lower portion 27 and forms a seat for a channel iron 19 passing through a rectangular aperture 29 in the member 27 immediately above the base 28.

In order to permit the second form of hangers to be adjusted so that all of them will hold the channel iron with an equal pressure, each of said hangers is provided with an intermediate loop section 30. The section 30 is preferably made of a rectangular U-shape and has its upper and lower legs 31 and 32 apertured near their bases to receive an adjusting screw bolt 33. The head 34 of the bolt 33 is located under the lower leg 32, while the other end of said bolt extends through the upper leg 31 and is provided with a nut 35. By turning the nut 35 on the bolt 33, the base 28 may be raised or lowered to any desired adjusted position.

In order to cause the upper leg 31 of the U-shaped loop to absorb shocks and vibrations from the floor above, the upper leg 31 is provided with a section 36 of reduced width, whereby said upper leg 31 is made more resilient than the lower leg 32.

As clearly shown in Figs. 4 and 5, a substantial space is left between the bottoms of the joists 11 and 26 and the tops of the channel irons 19, thus preventing any possible contact between said parts, which might transmit injurious vibrations from the floor above to the ceiling beneath.

One advantage of the present invention lies in the fact that the lower legs of the U-shaped loops are made stronger and stiffer than the upper legs thereof, so as to resist any sudden shocks from below which might occur during the operation of embedding the plaster of the ceiling on the metal lath.

A further advantage of the present invention is that the ceiling plaster is in contact with all metal parts, which cannot possibly absorb it during the setting process and cause streaks in the ceiling, as was the case with the former ceiling construction employing wooden "cross-furring" strips.

While there have been disclosed in this specification two forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

1. In a ceiling hanger, a portion adapted to be attached to a floor joist, a portion adapted to support a channel iron, an intermediate resilient section connecting said portions, said section being yieldable to sudden shocks from the floor above, and means for transmitting tensile stresses from the attaching portion to the supporting portion.

2. In a ceiling hanger, a portion adapted to be attached to a floor joist, a portion adapted to support a channel iron, an intermediate resilient weakened yieldable shock-absorbing section connecting said portions, and means for transmitting tensile stresses from the attaching portion to the supporting portion.

3. In a ceiling hanger, a portion adapted to be attached to a floor joist, a portion adapted to support a channel iron, an intermediate resilient yieldable shock-absorbing section connecting said portions, and means for transmitting tensile stresses from the attaching portion to the supporting portion, said supporting portion being offset from said attaching portion so as to avoid contact with said floor joist.

4. In a ceiling hanger, an upper portion for attachment to a floor joist, a lower portion offset from said upper portion for supporting a metal lath and plaster ceiling, an

intermediate U-shaped section connecting said attaching and supporting portions, and means connecting the two legs of said U-shaped section adapted to transmit tensile stresses, but adapted to yield under compression shocks from the floor above.

5. In a ceiling hanger, an upper portion for attachment to a floor joist, a lower portion for supporting a metal lath and plaster ceiling, an intermediate U-shaped section connecting said attaching and supporting portions, and means connecting the two legs of said U-shaped section adapted to transmit tensile stresses but adapted to yield under compression shocks from the floor above.

10. In a ceiling hanger, an upper portion for attachment to a floor joist, a lower portion for supporting a metal lath and plaster ceiling, an intermediate U-shaped section connecting said attaching and supporting portions, and means connecting the two legs of said U-shaped section adapted to transmit tensile stresses but adapted to yield under compression shocks from the floor above,

15. said lower supporting portion having a base to form a seat for a channel iron upon which said metal lath is hung.

20. In a ceiling hanger, an upper portion for attachment to a floor joist, a lower portion for supporting a metal lath and plaster ceiling, an intermediate U-shaped section connecting said attaching and supporting portions, and means connecting the two legs of said U-shaped section adapted to transmit tensile stresses but adapted to yield under compression shocks from the floor above,

25. the upper leg of said intermediate U-shaped section being weakened so as to absorb shocks transmitted thereto from the floor above.

30. In a ceiling hanger, an upper portion for attachment to a floor joist, a lower portion for supporting a metal lath and plaster ceiling, an intermediate U-shaped section

35. connecting said attaching and supporting portions, and means connecting the two legs of said U-shaped section adapted to transmit tensile stresses but adapted to yield under compression shocks from the floor above, the upper leg of said intermediate U-shaped section having a reduced part so as to absorb shocks transmitted thereto from the floor above.

40. In a ceiling hanger, an upper portion for attachment to a floor joist, a lower portion for supporting a metal lath and plaster ceiling, an intermediate U-shaped section connecting said attaching and supporting portions, and means connecting the two legs of said U-shaped section adapted to transmit tensile stresses but adapted to yield under compression shocks from the floor above, said hanger being constructed from bent strip metal.

45. In a ceiling hanger, an upper portion for attachment to a floor joist, a lower portion for supporting a metal lath and plaster ceiling, an intermediate U-shaped section connecting said attaching and supporting portions, and a threaded bolt and nut for connecting the two legs of said U-shaped section adapted to transmit tensile stresses but adapted to yield under compression shocks from the floor above.

50. In a ceiling hanger, an upper portion for attachment to a floor joist, a lower portion for supporting a metal lath and plaster ceiling, an intermediate U-shaped section connecting said attaching and supporting portions, and adjustable means connecting the two legs of said U-shaped section adapted to transmit tensile stresses but adapted to yield under compression shocks from the floor above.

55. In testimony whereof, I have affixed my signature to this specification.

PHILIP DUPHINEY.
